UNITED STATES PATENT OFFICE.

THOMAS E. DROHAN, OF CHICAGO, ILLINOIS, ASSIGNOR TO THE SIEMENS & HALSKE ELECTRIC COMPANY OF AMERICA, OF SAME PLACE.

ARC-LAMP.

SPECIFICATION forming part of Letters Patent No. 628,279, dated April 18, 1899.

Application filed August 8, 1898. Serial No. 688,044. (No model.)

To all whom it may concern:

Be it known that I, THOMAS E. DROHAN, residing at Chicago, Cook county, Illinois, have invented a certain new and useful Improvement in Arc-Lamps, (Case No. 176,) of which the following is a full, clear, concise, and exact description.

My invention relates to improvements in arc-lamps, and has for its object the provision of means for more effectively securing the feeding of the upper carbon and for preventing the release of the carbon when a predetermined portion thereof has been consumed.

My improvement is more particularly applicable to that class of arc-lamps wherein the upper carbon is carried in a tubular feeding device provided with a clutch which permits of the downward adjustment of the carbon within the carrier, whereby the length of the arc is maintained substantially constant.

The improvements of my invention may be briefly described as consisting of a roller movable within an inclined slot, said roller being adapted to engage the carbon within its tubular carrier and normally hold it securely in position. A pivoted clutch-releasing device is provided on the lamp-frame, which normally engages one side of the carbon and serves to disengage the roller-clutch when the tubular carbon-carrier is released by the feeding magnet of the lamp, the arc being adjusted in the usual manner through the medium of the said carrier and the electromagnet. When the carbon has been almost entirely consumed, the clutch-releasing device, being disengaged from the carbon, swings from the path of movement of the roller-clutch and prevents the further downward adjustment of the carbon and carbon-carrier.

My said invention will be more readily understood by reference to the accompanying drawings, wherein—

Figure 1 is a view in elevation of a portion of an arc-lamp, the same being partially in section to illustrate the device more clearly. Fig. 2 is a perspective view of the clutch-releasing device which I employ; and Fig. 3 is a sectional view on line 3-3 of Fig. 1, illustrating the roller-clutch device.

The same letters of reference are used to

designate like parts in the different figures of the drawings.

The lamp-frame *a*, a small portion of which is shown in Fig. 1, fixedly supports the lower carbon *b* and the feeding-electromagnet *c*. The core *c'* of said magnet carries the tubular upper-carbon carrier *d*, wherein the upper carbon *d'* is shown. A weight *e* is provided with a spindle, which bears upon the upper end of the carbon *d'* and serves to press the latter downward in the carbon-carrier, wherein it loosely fits. Upon the lower end of the said carbon-carrier is mounted a block *f*, wherein a diagonal slot *f'* is provided, which contains the roller-clutch *g*. The said roller normally engages one side of the upper carbon, the tubular carrier being diagonally cut away to permit of the said engagement, and by reason of positioning the roller in the inclined slot or way said carbon is firmly held in place by the roller.

Upon the lamp-frame *a* and in line with the axis of the upper carbon is pivotally mounted the clutch-releasing device *h*. (Shown in detail in Fig. 2.) This device consists of uprights *h'*, pivotally secured at their upper ends and terminating at their lower ends in horizontal arms *h*², which normally extend within the path of movement of the protruding ends of roller *g*. The weight *h*³, provided upon one side of the device, has a nose which normally engages the upper carbon, the tubular receptacle being cut away to permit of the said engagement and also the inward movement of the weight when the said carbon has been fed downwardly in its carrier past the point of engagement with the protruding nose.

The operation of the lamp will now be readily understood. Upon the lengthening of the arc between the upper and lower carbons the electromagnet *c* releases the carbon-carrier, which permits of the engagement of the ends of roller *g* with the arms *h*², thus causing the roller to rise slightly in the slot, whereby the upper carbon is fed downwardly a short distance past the roller-clutch. The carbon-carrier is immediately raised by the electromagnet, thus disengaging the roller-clutch from the releasing device and firmly seating the carbon within the carrier in its adjusted po-

sition. The weight e , which materially assists this adjustment, especially when the carbon has been decreased in length, follows the said carbon in its descent within the tube. 5 After many successive adjustments it will be seen that the upper end of the carbon d' will pass the protruding nose of the weight h^3 . Immediately this occurs the said weight swings the uprights h' out of line with the 10 axis of the upper carbon, thereby withdrawing the horizontal arms h^2 from the path of the roller-clutch. The protruding nose of the weight h^3 engages the upper end of the slot in the carbon-carrier and prevents the same 15 from moving downward. Inasmuch as the short end of the upper carbon is now firmly held in position within the carrier, it is impossible for the said end to drop out, with the attendant danger of short-circuiting the current and otherwise injuring the lamp. When 20 the arc has burned itself out, current will cease to flow through the lamp.

The roller-clutch device of my invention although particularly adapted for the use 25 herein described may readily be applied to various forms of arc-lamps and other analogous uses. In practice I have found it desirable to form my roller-clutch of unglazed porcelain, which effectively grips the carbon 30 and is not liable to injury from sparking. Its size and weight are determined by the requirements of the lamp. The device is highly efficient, in that it securely holds the carbon within its carrier and at the same time readily releases it when said carrier is downwardly fed. Furthermore, the upper carbon is 35 always held in perfect alinement with the lower one, since there is no chance of lateral movement and every adjustment is accurate and 40 exact, conducing to the most effective burning of the carbons.

The device is of extreme simplicity and there is little or no likelihood of its getting 45 out of order or being impaired through continuous use. It is apparent that modifications may be made in the apparatus shown and described in my present application without departing from the spirit of my invention, and I do not wish to be understood as limiting 50 my claims to the precise form of device herein shown and described.

I therefore claim, and desire to secure by these Letters Patent, the following:

1. The combination, in an arc-lamp, with a 55 carrier wherein is mounted the upper carbon thereof, of clutch mechanism associated with said carrier, comprising an inclined slotted part whereon is disposed a roller adapted to support the carbon, the said roller having 60 laterally-extended ends, a releasing device mounted in the lamp in position to engage the extending ends of the roller, and means for effecting the relative movement of the clutch mechanism and releasing device, whereby the 65 adjustment of the carbon is secured, substantially as described.

2. In a carbon-clutch mechanism for arc-

lamps, the combination with a tubular carbon-carrier d provided with an inclined slotted part f , of a roller g disposed within the 70 slot and having its ends extending beyond the same, the said roller being adapted to engage and hold the carbon in position, a releasing device h mounted in the lamp having arms h^2 extending within the path of the ends 75 of roller g , and electromagnetic feeding mechanism for securing the engagement of the extended ends of the roller with the releasing device, whereby the adjustment of the upper carbon is secured, substantially as described. 80

3. In a carbon-clutch mechanism for arc-lamps, the combination with a tubular carrier d for the upper carbon, of a clutch mechanism mounted thereon comprising a slotted block f , the slot therein inclining beyond one 85 wall of the carbon-carrier, a roller disposed within the slot, whose ends project therefrom, the said roller being adapted to engage the carbon and hold it in its position within the carrier, and a releasing device h having arms 90 h^2 normally extending in a position to engage the ends of the roller, whereby the roller is released and the carbon is downwardly fed within the lamp, substantially as described.

4. The combination in an arc-lamp, with a 95 vertically-adjustable carbon-carrier actuated by the feeding-magnet, of a clutch mechanism mounted upon the said carrier, comprising a slotted part and a roller disposed within the slot, normally engaging the carbon and 100 having its ends extending beyond the slot, a clutch-releasing device adapted to engage the extended ends of the roller and permitting the downward adjustment of the carbon within the carrier, and means for preventing the 105 release of the carbon after a predetermined portion thereof has been downwardly fed within the carrier, substantially as described.

5. In an electric-arc lamp, the combination 110 with a feeding-electromagnet c , of a carbon-carrier d wherein the upper carbon of the lamp is mounted, clutch mechanism associated with the said carrier, and a pivoted clutch-releasing device h secured upon the frame of the lamp and normally engaging the carbon, 115 said device being adapted to swing out of the path of the clutch device when the carbon has been fed past a predetermined point in the carrier, substantially as described.

6. The combination in an electric-arc lamp, 120 with the clutch mechanism of the upper carbon, of a pivotally-mounted clutch-releasing device h having arms normally adapted to engage the clutch mechanism and secure the 125 downward adjustment of the carbon, said device being disposed in engagement with the adjusted carbon and adapted to swing out of position for engaging said clutch mechanism when a predetermined portion of the carbon has been fed, and means for securing the 130 downward feeding of the carbon, substantially as described.

7. In an arc-lamp, the combination with a feeding-electromagnet, of a carbon-carrier

adapted to be actuated thereby, a clutch device adapted normally to hold the carbon securely in position, and a clutch-releasing device *h* pivoted to the lamp-frame, said device 5 being provided with arms *h*² normally adapted to actuate the clutch device and secure the adjustment of the carbon, the said releasing device being adapted to swing out of its position of engagement with the clutch mechanism when a predetermined portion of said carbon has been fed, substantially as described.

8. In an electric-arc lamp, the combination with the feeding-magnet *c*, of the carbon-carrier *d*, the roller-clutch *g* adapted to support said carbon within the carrier, the pivoted clutch-releasing device *h* adapted normally to engage the carbon and release the roller-clutch when the carbon-carrier is downwardly adjusted, substantially as described.

9. In an electric-arc lamp, the combination with the feeding-electromagnet *c*, of a tubular carbon-carrier *d*, wherein the upper carbon *d'* of the lamp is mounted, the roller-clutch *g* engaging the said carbon and adapted normally to secure it in its position within the carrier, a slot *f'* wherein the said clutch is movable, and a pivoted clutch-releasing device *h* mounted upon the frame of the lamp 25 and normally engaging the carbon *d'*, said device having arms *h*² extending within the path of movement of the roller-clutch *g*, whereby the same is released and the carbon is downwardly adjusted upon the actuation of the

carbon-carrier, the device *h* being further 35 adapted to swing out of position and prevent the engagement of the roller-clutch with the arms *h*², whereby the release of the carbon is prevented, substantially as described.

10. In an arc-lamp, the combination with 40 a clutch device controlling the movement of the upper carbon, of a clutch-releasing device *h* associated therewith, said device having an extended nose adapted alternatively to engage the carbon or support the same in its 45 final position within the clutch, and extended arms *h*² adapted to secure the release of the clutch while the carbon is engaged by said nose, substantially as described.

11. The combination in an arc-lamp, with 50 the clutch mechanism serving to support the upper carbon, of a clutch-releasing device *h* pivotally mounted in the lamp, said device having a part normally engaging the carbon, whereby the arms *h*² are held in position to 55 release the clutch mechanism, the device *h* being adapted to swing out of its releasing position and support the carbon in its final position within the clutch when a predetermined portion has been consumed, substantially as described.

In witness whereof I hereunto subscribe my name this 4th day of August, A. D. 1898.

THOMAS E. DROHAN.
